To all whom it may concern:

Be it known that I, William Burton, a citizen of the United States, residing at Chicago, in the county of Cook and State of Illinois, have invented a new, original, and ornamental Design for a Wallpaper or Similar Article, of which the following is a specification, reference being had to the accompanying drawing forming a part thereof.

In the drawing, the figure is a plan view of a wallpaper showing my new design.

I claim:

The ornamental design for a wallpaper or similar article, as shown.

WILLIAM BURTON.
